Paul M. Klein

UNITED STATES PATENT OFFICE.

KARL LEINS, OF NEW YORK, N. Y., ASSIGNOR OF ONE-THIRD TO ARTHUR LEINS AND ONE-THIRD TO FRANK REUTHER, BOTH OF NEW YORK, N. Y.

GARTER.

1,353,483.

Specification of Letters Patent. Patented Sept. 21, 1920.

Application filed April 3, 1920. Serial No. 370,932.

To all whom it may concern:

Be it known that I, KARL LEINS, a subject of Germany, and resident of New York, in the county of New York and State of New York, have invented certain new and useful Improvements in Garters, of which the following is a specification.

This invention relates to garters in general and particularly to the class consisting of helical spring members.

The objects of my invention are to provide a device of the class described having in addition to all the good qualities of similar devices the advantage of being almost indestructible, to afford good ventilation for the limb part to which it is attached, and not to impede in any way the blood circulation while nevertheless assuring absolute safety as to proper support of the article to be held in place.

Another object of my invention is to provide exchangeable stays or short-stops attached at the ends of my spring devices to specially constructed end plates projecting into the free space within the springs. These stays prevent the overexpansion of the spring members and may be adjusted to any desired length, thus serving as means for producing with the same spring members different sizes of garters.

A further object of my invention is to provide in connection with a garter simple and highly efficient fabric attaching means comprising a nonresilient, nonbendable member provided with a button-like extension and a hinged spring member, which, when compressed, swung toward and over that extension and then released, forms a perfect clamp device for holding the supported article.

The foregoing and other objects will be more fully apparent from the following description and the accompanying drawings, forming part of this specification in which:

Figure 1 is a side elevation of my device in normal condition.

Fig. 2 is a sectional view therethrough showing the detail construction.

Fig. 3 represents my device in expanded form.

Fig. 4 is a sectional view taken on line 4—4 of Fig. 1.

Fig. 5 is a perspective view of my fabric holding device.

Fig. 6 is the front elevation of same in compressed position.

Referring to the drawings, 10 represents a long and narrow spring member preferably made of rust-resisting wire such as German silver, nickel or other material. This spring member comprises an oval-shaped helical spring formed in the way seen in Fig. 4. Its end coils 11 and 12 are firmly held in box-like receivers 13 and 14, the ends 15 of which are slightly turned inward, thus providing a rest for the enlarged ends of the back or end plates 16 and 17.

The reduced portions 18 and 19 of these plates protrude through receivers 13 into the free space 20' (Fig. 4) formed by the spring and possess apertures 21 at their extreme ends.

A stay or expansion stop tape 22 is adjustably attached at these perforated plate ends and passes through the hollow space of the spring.

This stay is normally slack and serves, when the spring is pulled, for preventing the spring's expansion beyond its elastic limit and consequently its deformation due to over-expansion.

The expansion length of the spring may be varied according to desired sizes required for wear without changing the length of the normally compressed spring. This may be accomplished by shortening the stay 20 through moving the adjustable stay ends 22 toward each other. In order to do that, one or both of the end plates 16 and 17 are pulled out from their sockets or receivers 13 and 14, respectively, so that the adjustable ends 22 of the stay are exposed.

The end plates 16 and 17 are provided with male and female interlocking means 23 and 24 adapted to close the ends of spring member 10.

Secured to the female locking end of the spring member a link or buckle 25 is provided and serves as support for another spring-member 26 depending from the spring member 10 at substantially a right angle.

This depending spring member 26 is shorter and may be made wider than the

spring member 10, although its dimensions may be varied in use for different purposes.

The general construction of the short spring member 26 is similar to that of the 5 spring member 10.

It also comprises an oval-shaped helical spring the ends 27 and 28 of which are firmly held in receivers or sockets 29 and 30, respectively. The outer ends of these 10 sockets are bent inward, as indicated at 31, thus providing seals for end plates 32 and 33, having widened looped portions 34 and 35 forming hinged connections with links 25 and 36, respectively.

15 The reduced end plate portions 37 and 38 terminate in slots 39—through which pass adjustable end loops 40 of the stay or expansion stop 41.

Attached also to the link 36 is a fabric engaging device, comprising a stiff, non-bendable, non-resilient member 42 enlarged and looped at its attached end 43 and forming a hinge-like connection with link 36.

20 At or near the opposite end, the member 42 is provided with a button 44 or its equivalent which serves for engaging fabric of a hose or other articles to be supported by the garter.

25 Slipped through and hinged at the enlarged looped portion 43 is a spring member 45 comprising an endless wire arrangement adapted to engage the button 44. It consists of a coiled portion 46, acting as a spring, and continuing as a twist, indicated 30 at 47, into a pair of loops 48, which again continues in a straight direction, as seen at 49, toward the loop 43, where the wire lies 35 parallel to the adjacent part of link 36.

30 In Fig. 5 the device is shown in position 40 ready for receiving a fabric at the button 44. In Fig. 6 its wire portion is shown compressed by fingers 50 indicated in dashed lines. In this position the twisted portion 45 47 is open and ready to encircle the button 44 covered by the fabric which is to be held.

35 When the compressed wire member is swung against the stiff member 42 and, after passing the head of the button, is released, as shown in Fig. 2, the fabric is firmly held 50 in position.

The operation of the locking members 23 and 24 of the lower spring member 10 is evident from the drawings. The male end 23 is inserted into the longitudinal slot of female member 24 and then twisted so that the head of the male member rests in the transversal aperture of the female slot.

Having thus described my invention, I 60 reserve for myself the right to make changes or improvements on my device within the broad scope of my invention, for which I claim:

1. A garter comprising in combination, a longitudinal spring member made of an

oval-shaped helical spring, box-like receivers housing the ends of said springs, a female and a male locking plate projecting with their reduced ends into said receivers, a stop-tape connecting said locking plates, a buckle secured to the one receiver housing 65 the female locking plate, a depending shorter spring member attached to said buckle and comprising an oval-shaped helical spring, a pair of receivers engaging its ends, looped end plates passing into the receivers and having apertures, a stop-tape fastened with its ends in said apertures, one of the looped end plates engaging said buckle, a wire link, engaged by the other looped end plate, extending downward, a 70 fabric engaging member attached to said link and comprising a plate member having a broadened looped end, a button at its other end, a compressible wire spring member 75 adapted to engage said button and hinged at the looped end housing the link portion 80 fastened by said other looped end plates.

2. In a garter the combination of long and short spring members made of oval-shaped helical springs and disposed substantially at a right angle to each other, box-like receivers at the ends of each spring member adapted to house the ends of said coils of the springs, locking members provided at and extending into the receivers of 95 the long spring member, hinge-like end plates provided at and extending into the receivers of the short spring member, expansion stops provided within the hollow space of both spring members and attached 100 to said locking members and end-plates, respectively, a buckle connecting one receiver of the long spring member with one end-plate of the short spring member, a hinged buckle engaging the other end-plate, and a 105 fabric engaging device attached to said hinged buckle.

3. In combination with a garter as set forth, a fabric engaging device comprising a plate member looped at one end and hinged 110 at this looped end to the garter proper, a fabric engaging button associated with said plate member at its free end, a doubly looped spring wire snap hinged at the looped end of the plate and adapted to engage said button with its doubly looped portion when successively compressed and released.

4. In combination with a garter, a fabric engaging device composed of a nonresilient member having a button-like extension at 120 one end, a resilient member hinged at its other end said resilient member comprising an endless wire spring forming a spring coil near its hinged portion, a twist at its center portion, two loops at its free end, and straight side portions extending from the loops to the hinged end, the latter adapted 125 to be compressed, thus causing the twisted

portion to spread preparatory to engaging said button-like extension of the nonresilient member.

5. In combination with a garter, a fabric engaging device comprising a nonresilient, nonbendable member having a button-like fabric engaging extension near to or at one of its ends, and a spring member hinged at its other end, said spring member adapted 0 to engage said extension when successively compressed, swung toward and over the extension, and finally released.

6. A garter, comprising in combination, two spring members made of helical springs, 15 one member being longer and narrower than the other, hollow end caps housing the spring ends, end plates widened at one end and reduced at the other end projecting with their reduced ends into the hollow spaces 20 formed by the spring and resting with their widened ends against the outer portion of the caps, adjustable stays normally slack, connecting the reduced ends of said plates

and adapted to prevent the overexpansion of said spring members, a spring operated 25 fabric attaching member provided at one end of the shorter spring member, the other end of said shorter spring member being connected at substantially a right angle at one end of the longer spring member. 30

7. A man's garter comprising a longer and narrower and a shorter and wider spring member, both members made of oval-shaped helical springs and having internal adjustable stays for preventing their over-expansion, a fabric attaching member having a hinge-like connection at one end of the shorter spring member, and comprising a nonresilient button carrying portion and a resilient hinged part adapted to engage 40 said button carrying portion at will.

Signed at New York, in the county of New York and State of New York, this 1st day of April, A. D. 1920.

KARL LEINS.
